(57) **CLAIM**

The ornamental design for a microphone, as shown and described.

DESCRIPTION

FIG. 1 is a top and right side perspective view of a microphone showing the new design;

FIG. 2 is a bottom and left side perspective view of the microphone of FIG. 1;

FIG. 3 is a back view of the microphone of FIG. 1;

FIG. 4 is a left side view of the microphone of FIG. 1;

FIG. 5 is a front view of the microphone of FIG. 1;

FIG. 6 is a right side view of the microphone of FIG. 1;

FIG. 7 is a top view of the microphone of FIG. 1;

FIG. 8 is a bottom view of the microphone of FIG. 1; and,
FIG. 9 is a top and right side perspective view of the microphone of FIG. 1, shown in an environment of use,
mounted on a camera.

The difference in shading in the figures indicates a contrast of appearance and does not depict any particular color, texture, or material.

The evenly dashed broken lines shown in the drawings depict portions of the microphone that form no part of the claimed design. The dash-dot-dot broken lines shown in FIG. 9 depict environmental structure that forms no part of the claimed design.
